UNITED STATES PATENT OFFICE.

WALTHER KALB, OF LEIPZIG, GERMANY.

COLLAPSIBLE TUBE.

Application filed May 31, 1922. Serial No. 364,914.

To all whom it may concern:

Be it known that I, WALTHER KALB, a citizen of Germany, and a resident of Leipzig, Germany, have invented certain new and useful Improvements in Collapsible Tubes, of which the following is a specification.

My invention relates to improvements in tin tubes, and more particularly in tin tubes provided with spring actuated closing means adapted when compressing the tube to be opened by the matter enclosed therein. One of the objects of the improvements is to provide a tube which is simple in construction. Another object is to provide a tube in which even comparatively thick matter coming out of the tube is readily separated when relieving the pressure. A third object of the improvements is to provide a tube in which the matter comes out of the tube in the form of a cylindrical tube having a thin wall that collapses into a thin band when discharged. With these objects in view my invention consists in constructing the closing means in the form of a valve plug adapted to be unseated by internal pressure and to be forced on its seat by a spring attached thereto and located within the head of the tube, the valve seat being preferably provided by a comparatively sharp annular edge adapted to cut through the matter discharged from the tube.

In order that my invention be more clearly understood an example embodying the same has been shown in the accompanying drawing, in which the same reference characters have been used in all the views to indicate corresponding parts. In said drawing,

Fig. 1, is an elevation partly in section showing the upper part of the tube, and

Fig. 2, is a plan view of Fig. 1.

In the example shown in the figures the body *a* of the tube is made with a head *c*, said parts having a form permitting the manufacture of the tube in one operation according to the methods now in use for manufacturing tubes. The open head *c* carries a conical stopper or valve *d* having a stem *d'* extending into the tube and having a spring or springs *e* secured thereto. As shown the spring or springs are passed through a bore or bores made in the stem, and they are fixed in position by pressing

the stem together after inserting the same. The free ends *i* of the spring or springs bear on an annular shoulder *s* formed internally of the head, and they tend to pull the stopper *d* inwards and on its seat *g*. Upon compressing the tube the matter enclosed therein forces the stopper *d* from its seat against the action of the spring or springs *e*, and it comes out in the form of a cylindrical tube having a thin wall. Upon relieving the pressure the stopper is seated by the spring and severs the cylindrical tube on the outside of the container from the body of the matter remaining in the container.

In such cases in which the matter is comparatively tough I prefer to make the seat *g* in the form of a sharp annular edge adapted to cut through the film. To prevent the said edge from cutting into the conical portion of the stopper I provide the head *c* with radial internal ribs *h* bearing in the closed position of the stopper on the conical surface thereof.

While in describing the invention reference has been made to a particular example embodying the same I wish it to be understood that I do not limit myself to the construction shown in the drawing. For example, I do not limit myself to the conical form of the stopper or to the form of the spring or springs shown in the figures. Preferably the stopper and the spring or springs are coated with suitable matter such as lead, tin, or lacquer.

I claim:

1. A tube comprising a body formed with a head, said head provided with a tapered discharge opening and with internal radial ribs adjacent said opening, said opening and ribs forming a seat, an outwardly opening stopper shaped to seat within said tapered discharge opening, and a spring located within the tube and engaging the stopper whereby the latter is normally held in closed position.

2. A tube comprising a body formed with a head, said head provided with an annular tapered discharge opening and with internal radial ribs adjacent said opening, said opening and ribs forming a seat, an outwardly opening stopper shaped to seat within said tapered discharge opening, and a spring lo-

cated within the tube and engaging the stopper whereby the latter is normally held in closed position.

3. A tube comprising a body formed with a head, said head provided with a discharge opening, an outwardly opening stopper shaped to seat within said opening, a shoulder formed on the interior surface of the tube, and a bar spring wholly within the

tube and engaging the stopper and said 10 shoulder whereby the stopper is normally held in closed position.

In testimony whereof I hereunto affix my signature in the presence of two witnesses.

WALTHER KALB.
